PROCESS FOR THE MECHANICAL TRIMMING OF PIECES

Leon Saives, Billancourt, France, assignor to
Louis Renault, Billancourt, FranceApplication June 10, 1936, Serial No. 84,566
In France August 8, 1935

2 Claims. (CL. 90—11)

The present invention relates to a process for the mechanical trimming of pieces of any kind by the reproducing machine, and is chiefly applicable to the trimming of pieces for which there is a risk of deformation before or after the trimming, for instance in the trimming of airplane propellers consisting of a light alloy.

The airplane propellers which consist of a light alloy composed largely of aluminium or magnesium, comprise two, three or four blades, and the manufacture of each of such blades includes the following operations.

1. A forging which is followed by a pressing operation adapted to give to the blade a shape which comes as near as possible to its definite shape.

2. A treatment by which the metal is given the proper hardness and strength.

3. A trimming for the external shape of the blades.

This latter operation is performed at the present time either entirely by hand by the use of portable milling cutters or grinders, or by hand for the first face and by the reproducing machine for the second face. For the trimming of the first face by the reproducing machine, it is necessary to strongly secure the blade to a support by means of clamps, but without any distortion.

The present invention permits to obtain this result, and it consists in using as a support, a box containing freshly prepared plaster, upon which the piece to be trimmed, such as a blade, is lowered and is placed exactly in the position which the said piece is to occupy during the trimming. The bottom of the said box is planed smooth in order that it may be mounted on the table of the reproducing machine.

The accompanying drawing shows by way of example an embodiment of the invention which serves for the trimming of propeller blades.

Fig. 1 is a vertical longitudinal section of the propeller support.

Fig. 2 is a vertical cross section of the same. The device shown in the drawing comprises a

cast iron box 1 of suitable size having at its lower part a contact face 2 which is planed smooth in order that it may be mounted on the reproducing table. To secure the blade to be trimmed to the said support, freshly prepared plaster 3 is placed in the said box, and the blade 4 is lowered into the exact position which it is to occupy during the trimming of its upper face. When the plaster 3 has sufficiently set, the blade is firmly held in place by clamps 5—6—7—8 which are pressed against the blade by screws 9—10—11—12.

The operator begins by trimming the part between the clamps 5 and 6, and then removes the clamp 6 for the trimming at this point, after which he puts the clamp in place and then carries out the trimming between the clamps 6 and 7, and so on. When the upper face has been trimmed, the blade is reversed upon a device provided with a template, as in known practice, and the operator then trims the other face.

By operating in the manner above indicated, it is possible to effect the mechanical trimming of the first face of the blade, without any risk of deformation of this face after the trimming operation.

I claim:—

1. A process for mechanically trimming pieces of work having relatively large irregular flat surfaces to be machined, consisting in placing freshly prepared plaster in a box, mounting the piece of work on the plaster so that the latter conforms to the lower surface of the piece of work and is substantially coextensive therewith and so that the upper surface to be trimmed is exposed, permitting the plaster to set, removably and independently clamping the piece of work to the plaster at different points on the face to be trimmed and then finishing the upper surface of the piece of work.

2. The application of the process claimed in claim 1 to the mechanical trimming of the first face of a propeller blade.
